UNITED STATES PATENT OFFICE.

ARCHIBALD G. SHAVER, OF CHICAGO, ILLINOIS, ASSIGNOR TO THE REGAN SAFETY DEVICES COMPANY, INC., OF NEW YORK, N. Y., A CORPORATION OF NEW YORK.

SHUNTING OR TRIP DEVICE.

Application filed December 29, 1921. Serial No. 525,790.

To all whom it may concern:

Be it known that I, ARCHIBALD G. SHAVER, a citizen of the United States, residing at Chicago, in the county of Cook and State 5 of Illinois, have invented certain new and useful Improvements in Shunting or Trip Devices, of which the following is a specification.

This invention relates to a train control 10 system, and more particularly to a train control system of the induction type, and has special reference to the provision of an inductive shunting or tripping apparatus adapted especially for use with the train 15 control systems disclosed in my copending applications Ser. No. 506,595 of October 10, 1921 and Ser. No. 515,242 of November 13, 1921.

Among the more important objects of my 20 present invention are the provision of co-operative vehicle and roadside magnetic or inductive apparatus including magnetic shunting or tripping instrumentalities for influencing train control means to condition 25 the latter for control by independent vehicle and roadside mechanism operable in response to traffic conditions; the further provision of such vehicle and roadside magnetic apparatus in which a three-element 30 or three coil vehicle carried means comprising two energy transmitting coils normally coupled to an energy receiving coil for transference of energy therebetween is arranged for movement over a roadside magnetic element, the latter being operative for 35 shunting the energy receiving coil in the movement of the vehicle; the further provision of apparatus of this nature in which the shunting of the receiving coil effects 40 the tripping of vehicle control means; the still further provision of apparatus of this nature in which substantially complete magnetic shunting of the energy receiving coil is made effective by neutralizing any 45 magnetic leakage through the receiving coil taking place during shunting activity; and the provision of apparatus of the nature referred to in which the neutralization of magnetic leakage is obtained by producing 50 an opposed inductive coupling between the coils.

To the accomplishment of the foregoing and such other objects as may hereinafter appear, my invention consists in the elements and their relation one to the other,

as hereinafter particularly described and sought to be defined in the claims, reference being had to the accompanying drawing which shows preferred embodiments of my invention, and in which:

Fig. 1 is a diagrammatic view of a stretch of track and of the vehicle carried apparatus in a position cooperating with the roadside magnetic element for effecting a shunting or tripping action, the vehicle carried apparatus being displaced laterally for purposes of clarity,

Figs. 2, 3 and 4 are views of modifications in which complete shunting action is accomplished by a neutralization of magnetic leakage between the coils,

Fig. 5 is a view of the vehicle carried apparatus in use with a two element relay, and

Fig. 6 is a view of the same in use with a single element relay.

Referring now more in detail to the drawings, the present invention as heretofore mentioned comprehends the provision of co-operative vehicle and roadside magnetic or inductive means for producing a given control condition in train control mechanism of the type disclosed in my copending application Ser. No. 515,242 above mentioned for conditioning said train control mechanism for operation by additional cooperating vehicle and roadside magnetic means. Referring now to Figs. 1 and 5 of the drawings, the vehicle carried mechanism comprises a plurality of inductively coupled coils M_1 , M_2 and M_3 , the coils M_1 and M_2 comprising energy transmitting coils and the coil M_3 comprising an energy receiving coil arranged between the energy transmitting coils, the three coils being in the nature of a transformer having a pair of outer primary windings and an inner or intermediate secondary winding all wound on linear cores arranged in parallel relation. The energy transmitting coils M_1 and M_2 are connected in series to a vehicle source of energy such as the alternating current generator G as clearly shown in the figures, the energy receiving coil M_3 being connected to a vehicle control device such as the relay R which may comprise a two element relay having the elements r and r' ,

the said energy receiving coil being connected to the element r of said relay, and the other element r' being connected across

- the lines to the generator G as clearly appears in the figures. For the purpose of correcting or adjusting the phase relation of the current in the circuit of the primary 5 windings M_1 and M_2 , I may provide a condenser C arranged in the said circuit.
- Cooperating with the inductively coupled coils or three element transformer, there is provided for each section or block of the 10 track an inert track element I, the inductively coupled coils being adapted to move over and cover the track element I in the passage of the vehicle thereover. With this construction it will be seen that normally 15 when the train is running between track elements magnetic flux is transmitted from the primary coils M_1 and M_2 to the intermediate secondary coil, inducing a current therein sufficient to energize the relay element r to normally keep the armatures controlled thereby in a closed condition. When the transformer covers a track element I, the magnetic flux flows from the primary coils to and through the inert track element 20 I, resulting in a diverting or shunting of magnetic flux from the receiving coil M_3 , the shunting of the said receiving coil resulting in a reduction in the energizing current of the relay element r and an effective deenergization of the latter, with the result that the armatures controlled thereby are opened for tripping other train control means.

Experiments seem to indicate that the theory of operation or action of the transformer combination $M_1-M_2-M_3$ and of the inductive influence of the inert inductor I to produce the magnetic shunting of the secondary of the transformer or shunting or diverting of the lines of flux may be taken substantially as follows, it being understood, however, that this theory of operation is given by way of explanation only, and not by way of limitation of the invention:

If we let M =Total MMF, the magneto motive force in the magnetic circuit of the transformer $M_1-M_2-M_3$.

ϕ =Total flux.

R_p =Reluctance of the primary coils.

R_r =Reluctance of the remainder of the 50 magnetic circuit.

Then

$$M = \phi (R_p + R_r) \quad (1)$$

Transposing,

$$M - \phi R_p = \phi R_r \quad (2)$$

Equation (1) shows that the total magneto motive force is made up of the magneto motive force active on the primary and the magneto motive force active on the remainder of the magnetic circuit. In equation (2) the quantity ϕR_r may be considered the magnetic potential difference which is effective on the remainder of the magnetic circuit for energizing purposes and more particularly for energizing the secondary M_3 .

When the vehicle carried transformer $M_1-M_2-M_3$ moves over the track element I, two effects are produced, substantially as follows:

(a) When the vehicle carried transformer inductor moves over the track element the flux ϕ increases and since R_p is constant, the product ϕR_p increases, and from equation (2) it will be seen (assuming M to remain constant) that the effective magnetic potential difference ϕR_r operative for energizing purposes decreases so that the energizing current for the relay R is effectively decreased.

(b) The magneto motive force M, however, does not remain constant. When the vehicle carried transformer moves over the track element, the reactive effect on the vehicle carried inductor due to the decrease in reluctance in the magnetic circuit produces a decrease in the magneto motive force M since the inductance of the energizing primary coil is increased with a corresponding decrease in energizing current. The magneto motive force (ampere turns) therefore is decreased and thus the difference between this and ϕR_p is decreased still further, the resulting magnetic potential difference active for energizing the secondary being thereby still further reduced. Experiments appear to determine that the decrease in the magnetic potential difference due to the first effect (a) is the more predominant of the two, the resultant change being due substantially to this factor, the magnetic flux through the secondary being therefore actually shunted or diverted, although part of the total magnetic flux is somewhat decreased due to the second mentioned factor (b).

For the purpose of assuring the complete deenergization of the relay element r during the tripping or shunting action, I provide means for neutralizing or opposing any energizing current in the circuit of said relay element produced by any magnetic leakage or residual between the primary and secondary coils of the transformer. To this end I provide a second inductive coupling between the primary and secondary coils, and more particularly between one of said primary coils and the said secondary coil, for producing a magnetic flux in opposition to any magnetic flux resulting from the leakage between the coils, such a construction being shown in Figs. 2 to 4 of the drawings. In Fig. 2 of the drawings the central coil M_3 and one external coil M_1 are looped together by an opposing or bucking coil having a winding W_{ss} over the coil M_3 and a winding W_{1s} over the coil M_1 , the said windings being of relatively few turns and functioning to produce a current in the coil M_3 in opposition to the actuating current, the construction being such that the oppos-

ing current is sufficient to neutralize the actuating current resulting from any magnetic leakage between the coils.

In Fig. 3 an alternative form of arrangement is shown, in which the bucking or opposing coil is produced by a winding W_4 on the core of the coil M_1 of a few turns in series with the central coil M_3 . In Fig. 4 the same result is accomplished on the auto-
10 transformer principle with the separate coil eliminated, a few turns W_4 of the coil M_1 being connected to the secondary coil M_3 for this purpose.

In lieu of employing a two-element relay
15 for operating the train controlling mechanism, it will be apparent that other forms of relay may be employed as shown for example in Fig. 6, in which a single element relay R is connected to the secondary coil M_3 of the transformer.

The operation of my train control apparatus will in the main be apparent from the above detailed description thereof. It will be apparent that as the vehicle carried mechanism moves over and in proximity to the inert track element I, that the magnetic flux from the secondary coil M_3 will be shunted for deenergizing the relay R , the magnetic flux under these conditions flowing from the primary coils M_1 and M_2 to and through the inert track element I. It will be further seen that for effecting the complete deenergization of the control relay R , any magnetic leakage between the primary and secondary coils taking place during shunting or tripping action is effectively opposed and neutralized by the secondary inductive coupling between the said coils.

While I have shown my device in the preferred forms, it will be apparent that many changes and modifications may be made in the structure disclosed, without departing from the spirit of the invention, defined in the following claims.—

1. In combination, vehicle mechanism comprising a plurality of energy transmitting coils, an energy receiving coil inductively coupled thereto, and roadside mechanism comprising a magnetic member operative when the vehicle mechanism moves in proximity thereto for magnetically shunting the energy receiving coil.

2. In combination, vehicle mechanism comprising a transformer including a pair of primary coils and a secondary coil coupled thereto, and roadside mechanism comprising a magnetic shunt member operative when the vehicle mechanism moves in proximity thereto for shunting the magnetic flux from the secondary coil of the transformer.

3. In a train control system, in combination, vehicle mechanism comprising a plurality of primary coils and a secondary coil coupled thereto, vehicle control means influenced by said secondary coil, a source of

energy connected to the primary coils, and roadside mechanism comprising a magnetic member operative when the vehicle mechanism moves in proximity thereto for magnetically shunting said secondary coil for operating said vehicle control means.

4. In combination, vehicle mechanism comprising a source of energy, a controlling relay, three parallelly arranged inductively coupled coils including outer coils and an inner coil, the outer coils being connected to the source of energy and the inner coil to the controlling relay, and cooperative roadside mechanism comprising a magnetic element operative for magnetically shunting the inner coil of the inductively coupled coils when the latter are moved in proximity to the said magnetic element.

5. In combination, vehicle mechanism comprising a source of energy, a controlling two-element relay, three parallelly arranged inductively coupled coils including outer coils and an inner coil, the outer coils being connected to the source of energy and the inner coil to one element of the controlling relay, with the other element of the relay connected to the said source of energy, and cooperative roadside mechanism comprising an inert magnetic element.

6. In combination, vehicle mechanism comprising a plurality of energy transmitting coils, an energy receiving coil inductively coupled thereto, roadside magnetic means operative for magnetically shunting the energy receiving coil in the movement of the vehicle over a roadway, and provisions for neutralizing magnetic leakage through said receiving coil.

7. In combination, vehicle mechanism comprising a transformer including a pair of primary coils and a secondary coil coupled thereto, roadside mechanism comprising a magnetic shunt member operative in the movement of the vehicle for substantially shunting the magnetic flux from the secondary coil, and provisions for neutralizing magnetic leakage through said secondary coil.

8. In combination, vehicle mechanism comprising a source of energy, a controlling relay, a plurality of primary coils and a secondary coil coupled thereto, the primary coils being connected to the said source of energy and the secondary coil to the controlling relay, a roadside magnetic device for shunting the magnetic flux from the secondary coil in the movement of the vehicle, and provisions for neutralizing magnetic leakage through said secondary coil during the shunting thereof whereby the energizing current for said relay is reduced to a minimum.

9. In combination, vehicle mechanism comprising inductively coupled coils, roadside mechanism comprising a magnetic member operative when the vehicle mechanism

- moves in proximity thereto for magnetically shunting one of said coils, and provisions for neutralizing magnetic leakage through said shunted coil.
- 5 10. In combination, vehicle mechanism comprising inductively coupled coils, roadside mechanism comprising a magnetic member operative when the vehicle mechanism moves in proximity thereto for magnetically shunting one of said coils, and provisions for neutralizing magnetic leakage through said shunted coil, the said provisions comprising an opposing inductive coupling between said coils.
- 10 11. In combination, vehicle mechanism comprising inductively coupled coils, roadside mechanism comprising a magnetic member operative when the vehicle mechanism moves in proximity thereto for magnetically shunting one of said coils, and provisions for neutralizing magnetic leakage through said shunted coil, the said provisions comprising a coupling between the coils for producing a magnetic flux in the shunted coil 25 in opposition to the leakage flux therein.
12. In combination, vehicle mechanism comprising a pair of energy transmitting coils, an energy receiving coil inductively coupled thereto, roadside mechanism comprising a magnetic member operative when the vehicle mechanism moves in proximity thereto for magnetically shunting the energy receiving coil, and provisions for neutralizing magnetic leakage through said receiving coil.
- 30 13. In combination, vehicle mechanism comprising a source of energy, a controlling relay, coils comprising a pair of primary coils and a secondary coil coupled thereto, the primary coils being connected to the source of energy and the secondary coil to the controlling relay, roadside mechanism including a magnetic element for shunting said secondary coil in the movement of the vehicle, and provisions for neutralizing magnetic leakage through said secondary coil to minimize the energizing current of said controlling relay.
- 40 14. In combination, vehicle carried mechanism comprising a three-element transformer having a primary and a secondary and a roadside mechanism for magnetically shunting the secondary in the movement of the vehicle carried mechanism over the roadside mechanism.
- 45 15. In combination, vehicle mechanism comprising a source of energy, a train controlling device, a plurality of energy transmitting coils connected to said source of energy, an energy receiving coil inductively coupled to said energy transmitting coils and connected to said train controlling device, and provisions for neutralizing magnetic leakage through said energy receiving coil under predetermined conditions.
- 50 16. In combination, vehicle carried mechanism comprising a three-element transformer having a primary and a secondary, vehicle carried control means controlled by said secondary, a vehicle carried source of energy connected to the primary, and a roadside mechanism for magnetically shunting the secondary in the movement of the vehicle carried mechanism over the roadside mechanism.
- 55 17. In combination, vehicle carried mechanism comprising a three-element transformer having a primary and a secondary, roadside mechanism for magnetically shunting the secondary in the movement of the vehicle carried mechanism over the roadside mechanism, and provisions for neutralizing magnetic leakage through said secondary.
- 60 18. In combination, vehicle mechanism comprising a source of energy, a train controlling device, a three-element transformer having a primary connected to the source of energy and a secondary connected to the train controlling device, and provisions for neutralizing magnetic leakage through said secondary under predetermined conditions.
- 65 19. In combination, vehicle mechanism comprising an energy device, a controlling device, three inductively coupled coils, including outer coils and an inner coil, the outer coils being connected to one of said devices and the inner coil being connected with the other of said devices.
- 70 20. In combination, vehicle inductive mechanism comprising an energy transmitting coil set and energy receiving coil set inductively coupled thereto; one of said sets comprising a plurality of coils, a source of energy connected to one of said coil sets and a train controlling device connected to the other of said coil sets.
- 75 21. In combination, vehicle inductive mechanism comprising an energy transmitting coil set and energy receiving coil set inductively coupled thereto; one of said sets comprising a plurality of coils, a source of energy connected to one of said coil sets and a train controlling device connected to the other of said coil sets, and cooperative roadside mechanism comprising a magnetic element operative for magnetically shunting the energy receiving coil set.
- 80 22. In combination, vehicle mechanism comprising a source of energy, a train controlling device, an energy transmitting coil connected to said source of energy, an energy receiving coil inductively coupled to said energy transmitting coil and connected to said train controlling device, and provisions for neutralizing magnetic leakage through said energy receiving coil under predetermined conditions.
- 85 23. In testimony whereof I affix my signature
ARCHIBALD G. SHAVER
